UNITED STATES PATENT OFFICE

99,943

DESIGN FOR A CENTRAL HOUSE HEATING APPARATUS CASING

Clarence R. T. Hess, Prairie View, Ill., assignor to
L. J. Mueller Furnace Company, Milwaukee,
Wis., a corporation of Wisconsin

Application March 21, 1936, Serial No. 61,730

Term of patent 14 years

To all whom it may concern:

Be it known that I, Clarence R. T. Hess, a citizen of the United States, residing at Prairie View, in the county of Lake and State of Illinois, have invented a new, original, and ornamental Design for a Central House Heating Apparatus Casing, of which the following is a description, reference being had to the accompanying drawing, forming part thereof.

The figure is a perspective view of a central

house heating apparatus casing showing the front and one side of my new design.

The rear of the casing is substantially like the side shown, and the top of the casing is open within the rectangular frame border.

I claim:

The ornamental design for a central house heating apparatus casing, substantially as shown and described.

CLARENCE R. T. HESS.
